THERMOCHROMIC THERMOMETER

Philip L. Van Kersen, P.O. Box 40423,
Indianapolis, Ind. 46240

Filed Dec. 18, 1974, Ser. No. 533,867

Term of patent 14 years

Int. Cl. D10—04

U.S. Cl. D10—57

Fig. 1

Fig. 3

Fig. 2

FIG. 1 is a front elevational view of a thermochromic thermometer showing my new design;

FIG. 2 is a rear elevational view thereof; and

FIG. 3 is a left side elevational view, the right side being a mirror image thereto.

I claim:

The ornamental design for a thermochromic thermometer, as shown and described.
